ABSTRACT

A current limiting device as contained in a two-part housing, each part including a terminal. An electrical conductor is mounted between the terminals and has the characteristic of vaporizing with increasing current flow through the conductor. An insulator partially encloses a portion of the conductor and is itself surrounded by the conductor. An insulating member separates each part of the two-part housing and the inner wall of the juncture of the two-part housing is engaged by the periphery of the insulating member which also engages the outer surface of the insulator for retaining the insulator, the conductor surrounding the insulator exerting a compressive stress onto the surfaces of the insulator which opposes the tensile stresses generated therein as a result of pressure developed from vaporization of the conductor.

FIG-1

FIG-2

FIG-3

CURRENT LIMITING DEVICE

The invention relates to a current limiting device, comprising a housing with two terminal members, a conductor mounted within the housing between the terminal members. The conductor at high current flow exhibits a resistance increase such that the current flow will be limited, which conductor is at least partially enclosed in an insulator. Structure is provided between the inner wall of the housing and the outer wall of the insulator, which exerts external prestressing forces onto the insulator, whereby compressive stresses are caused in the insulator material, which are oppositely directed to the tensile stresses generated therein due to the pressure developed in the portion of the conductor enclosed in the insulator at high current flow. A device of this kind is known from the German Auslegeschrift No. 2,162,991.

The known device is a current limiter, which operates at a predetermined current flow therethrough, at which the conductor material evaporates due to the ohmic losses occurring therein, whereby the electric resistance of the current limiter will increase considerably and the current flow will be limited to such an extent that the current can be switched off by means of a switching apparatus of relatively small switching capacity connected in series with the current limiting device. The conductor is partially enclosed in a tubular insulator of ceramic material, and if the conductor material which is present in the insulator evaporates, a very high pressure is generated therein, so that high tensile stresses will arise in the ceramic material of the insulator. Since ceramic material is relatively weak for tensile stresses but on the contrary very strong for compressive stresses, the insulator in the known device is put under a high prestress, so that if the device operates still a compressive stress or a very small tensile stress will be present in the ceramic material. The prestress is achieved by applying an insulating filling material between the tubular insulator and the surrounding housing, the said filling material is poured in the interspace at relatively high temperature. Then the assembly is cooled down to room temperature. Since the thermal expansion coefficient of the filling material is larger than that of the ceramic material of the insulator, and the thermal expansion coefficient of the housing in turn is larger than that of the filling material, a compressive stress is built up in the ceramic insulator and a tensile stress is built up in the housing during the cooling process of the assembly. As a consequence the housing is relatively highly stressed, also under normal circumstances, and the tensile stress in that housing will increase considerably if the current limiter operates, so that the housing has to be made very heavy.

The object of the invention is to eliminate such a disadvantage and to provide a current limiter, of which the housing under normal circumstances is not stressed and the prestress exerted on the insulator is built up if the current limiter operates.

The invention provides a device of the kind stated above, wherein the insulator is arranged practically completely in the material of the conductor and at its exterior is provided with an annular insulating member, which engages the inner wall of the housing. The housing consists of two parts, which are secured to one another with an insulating body sandwiched therebe-

tween. The annular member engages the inner edge of the insulating body.

If the device according to present invention operates in response to a high current flow, the ceramic tube is practically completely embedded in a liquid or gaseous conductor material, so that the ceramic material of the insulator is compressively loaded from all sides. The surrounding housing need only be capable of resisting that pressure and need not be dimensioned for a constant prestress.

The device may be arranged so that the insulator is tubular shaped and the annular member is an O-ring, which is arranged approximately in the middle of the insulator. As an alternative it is also possible to locate the O-ring at one end of the insulator.

The invention will now be explained further in reference to the drawing, in which:

FIG. 1 is a longitudinal section of the device according to present invention,

FIG. 2 is a longitudinal section of an other embodiment, and

FIG. 3 is a cross section according to the line III—III in FIGS. 1 and 2.

Referring to FIG. 1 the housing of the current limiter consists of two metallic cylindrical parts 1 and 2, which are secured to one another through an intermediate disc of insulated material 3. The securing means have not been illustrated, but they may take the form of draw bolts. In the bore of the cylindrical housing is positioned a ceramic tube 4, which is practically completely surrounded by the conductor material 7. The conductor material 7 may be a liquid metal, such as mercury, an alkaline metal or any other metal, which in liquid condition exhibits a sufficient increase of resistance. The tube 4 is retained in the bore by the O-ring 5, which surrounds the exterior of the tube 4, and also engages the inner edge of the disc 3. A part of the bore serves as expansion space 8, and the conductor material 7 is sealed by means of a piston 6. The space 8 may be filled with nitrogen for example. At the ends of the housing parts 1 and 2 the respective terminal members 9 and 10 are provided, which in present case take the form of bolts.

If the device is connected into an electric circuit, an electric current will flow from the terminal member 9, through the housing part 1, the conductor material 7 in the bore of the tube 4, the housing part 2 and the terminal member 10. The dimensions of the bore in the tube 4 and the nature of the conductor material 7 determine the magnitude of the current flow, at which the current limiter will operate. As soon as this happens, a high pressure is generated in the conductor material 7 in the bore, and this high pressure immediately propagates to the areas in the conductor material 7 at the exterior of the tube 4, so that the tube 4 is loaded with compressive forces from all sides.

In FIG. 2 another embodiment of the device according to present invention is illustrated, and the same reference numerals are used as in FIG. 1. The difference with the first embodiment is that the ceramic tube 4 is retained by the O-ring, not as in FIG. 1 in the middle, but at one of its ends.

What is claimed is:

1. A current limiting device, comprising:
a two-part housing each including a terminal member;

an electrical conductor mounted between each of said terminal members and having an increasing resistance characteristic with increasing current flow whereby said conductor vaporizes; an insulator for at least partially enclosing a portion of said conductor and surrounded by said conductor; and

an insulating member separating each part of said two-part housing, the periphery of said insulating member engaging the inner wall of the juncture of said two-part housing and said insulating member also engaging the outer surface of said insulator for retaining said insulator, said conductor surrounding said insulator for exerting compressive stresses onto the surfaces of said insulator for opposing the tensile stresses generated within the insulator as a

result of the pressure developed from said conductor at increased current flow.

2. A current limiting device as in claim 1 wherein said insulator is tubular shaped and said insulating member includes an O-ring mounted in substantially the middle region of said insulator.

3. A current limiting device as in claim 1 wherein said insulator is tubular shaped and said insulating member includes an O-ring mounted at the end portion of said insulator.

4. A current limiting device as in claim 1 further comprising a gas-filled chamber at one end of said conductor and a piston separating said gas-filled chamber and said conductor.
